UNITED STATES PATENT OFFICE

CONNOR C. CHAMBERS, OF CHICAGO, ILLINOIS.

RAILROAD-FROG.

1,002,964.

Specification of Letters Patent. Patented Sept. 12, 1911.

Application filed May 5, 1911. Serial No. 625,302.

To all whom it may concern:

Be it known that I, CONNOR C. CHAMBERS, a citizen of the United States, and a resident of the city of Chicago, county of Cook, 5 and State of Illinois, have invented certain new and useful Improvements in Railroad-Frogs, of which the following is a specification.

My invention relates to improvements in 10 frogs used in railroad construction and has for its object the production of a device of this character which will be of improved construction and efficient in operation.

Other objects will appear hereinafter.

With these objects in view my invention 15 consists in a railroad frog characterized as above mentioned and in certain details of construction and arrangement of parts as will be hereinafter fully described and more 20 particularly pointed out in the appended claims.

My invention will be more readily understood by reference to the accompanying drawings forming a part of this specification, and in which,

Figure 1 is a perspective view of a railroad frog embodying my invention, Fig. 2 is a fragmentary detail section taken on substantially line $\alpha-\alpha$ of Fig. 1, and Fig. 3 is 30 a fragmentary section taken on line $y-y$ of Fig. 2.

The preferred form of my construction as illustrated in the drawings comprises a metallic block 1 which is preferably of the 35 peripheral form shown, said block being poured about the adjacent ends of rails 2. The latter may be of any ordinary construction or design, that illustrated being a conventional grooved rail; said rails project- 40 ing from said block any suitable distance for connection with adjacent rail sections of the track. The block 1 is shown formed solid but it is understood that if desired the same may be cored to reduce the weight 45 thereof. Formed in the upper side of the block 1 are grooves 3 which register as shown with the grooves formed in the upper sides of said rails 2. Also formed in the upper side of the block 1 centrally there- 50 in is a recess 4 preferably rectangular in outline and comparatively shallow. Arranged in the recess 4 is a wear-plate 5, the same being of such dimensions and of such formation as to be adapted to be snugly received in said recess; the construction being 55 such however that removal of said wear-

plate in order to effect renewal thereof may be readily effected. Said wear-plate is formed of a suitable hardened metal and is provided in its upper side with grooves 3' 60 which register with the grooves 3 in the block 1. Formed at the periphery of the wear-plate 5 preferably at each side thereof is a downwardly and outwardly projecting finger 6; the fingers 6 engaging slots 7 65 formed for the reception thereof in the adjacent portions of the block 1. The slots 7, as will be observed, open laterally as well as upwardly, wedge members 8 being inserted therein into engagement with the 70 upper sides of the fingers 6. Said wedge members 8 are formed with inclined shoulders 9 adjacent their upper ends, said shoulders 9 engaging against correspondingly formed surfaces of said slots so that when 75 said wedges are driven inwardly the same will be forced downwardly against the fingers 6 to securely fasten the plate 5 in position. Thus the latter is detachably secured in operative position in the block. 80 The wedge members 9 are locked in position by means of wedge members 10 which are inserted into slots 11 provided in the exteriorly projecting outer ends of the fingers 6, said wedge members 10 abutting against 85 the outer ends of the wedge members 8 as clearly shown in Fig. 2. Cotter pins 12 removably arranged in the lower ends of the wedge members 10 for engagement against the under sides of the projections 6 serve 90 to lock said wedge members 10 against accidental displacement.

With a construction as set forth then, it will be observed that the wear-plate 5 is secured in the block 1 in such a manner as 95 to be adapted to be readily and expeditiously removed and upon the same becoming worn or otherwise disabled another plate of similar design may be readily and quickly arranged in its place. The construction is 100 such that the plate 5 may at all times be rigidly secured in position, provision being made to effect this purpose by reason of the peculiar construction of the wedge members 8. If it is desired to elevate the wear-plate, 105 a sheet or plate of metal may be arranged thereunder upon the bottom of the recess 4. In removing the wear-plate the wedge members 10 after removal of the cotter pins 12 are first withdrawn. The wedge members 8 110 are then removed whereupon removal of the plate 5 may be readily and quickly ef-

fected by tapping upon the exteriorly projecting ends of the fingers 6.

A railroad frog of the construction set forth is durable and economical, and through 5 its provision an intersection may be renewed without necessitating the renewal of the entire frog, renewal of the intersection being effected economically and expeditiously in the manner above described.

10 While I have illustrated and described the preferred form for carrying my invention into effect, this is capable of variation and modification without departing from the spirit of the invention. I therefore do not 15 wish to be limited to the precise details of construction set forth, but desire to avail myself of such variations and modifications as come within the source of the appended claims.

20 Having described my invention what I claim as new and desire to secure by Letters Patent is:

25 1. In a railroad frog, the combination of a base block having wheel flange grooves and a central recess formed in the upper side thereof; a wear-plate arranged in said recess and having grooves in its upper side registering with the grooves in said base block; downwardly and outwardly projecting fingers provided at the periphery of said wear-plate engaging slots in the adjacent portions of said block; and wedge members adapted to be driven into said slots into engagement with the upper sides of said fingers for 30 35 removably securing said wear-plate in position in said recess, substantially as described.

2. In a railroad frog, the combination of a base block having wheel flange grooves and a central comparatively shallow recess formed

in the upper side thereof; a wear-plate arranged in said recess and having grooves in its upper side registering with the grooves in said base block; outwardly extending projections formed upon said plate at the periphery thereof engaging slots formed for the reception thereof in the adjacent portions of said base block; and wedge members adapted to be moved horizontally into engagement with said slots to engage against the upper sides of said projections for removably securing said wear-plate in position in said recess, substantially as described. 40 45 50

3. In a railroad frog, the combination of a base block having wheel flange grooves and a central comparatively shallow recess formed 55 in the upper side thereof; a wear-plate arranged in said recess and having grooves in its upper side registering with the grooves in said base block; a plurality of outwardly extending projections formed 60 upon said plate at the periphery thereof engaging slots formed for the reception of said projections in the adjacent portions of said block; wedge members adapted to be moved horizontally inwardly into engagement with said slots to engage against the upward sides of said projections, inward movement of said wedge members effecting depression of said projections; and means 65 for locking said wedge members in operative 70 position, substantially as described.

In testimony whereof I have signed my name to this specification in the presence of two subscribing witnesses.

CONNOR C. CHAMBERS.
